CHANGING DISPLAY APPARATUS

George Edgar Slack, Ruislip, England

Application May 17, 1939, Serial No. 274,248
In Great Britain March 25, 1938

4 Claims. (Cl. 40—84)

This invention relates to changing display apparatus. The invention is primarily intended for displaying flexible sheets bearing printed matter and is particularly, though not exclusively, adapted for displaying a series of news bills (commonly known as placards). Hitherto it has been customary to mount a placard on a flat board and to display as many of these boards as possible outside a shop or in some other prominent position, but the number of such boards which can be employed is often limited by reason of space and in many cases space for one or two boards only is available.

The object of the present invention is to provide a display device in which rolled-up sheets, e. g. placards, are housed and periodically unrolled for display, so that a series of sheets are displayed in a desired sequence.

Broadly, the invention comprises means for accommodating a supply of rolled-up sheets, means for releasing or feeding the rolled-up sheets singly, means for unrolling the singly-fed rolled sheet into an open displaying condition, and means for rolling-up the sheet after a pre-arranged display period.

The rolled-up sheets are preferably stacked horizontally in a housing within which they move from one end to the other, the sheets being fed from one, i. e. the delivery end of the housing and returned automatically to the other, i. e. the receiving end of the housing. The sheets may move unaided, e. g. by gravity, through the housing, be released or fed singly from the bottom of the stack and returned after display to the top of the stack. With a view to employing the apparatus to the best advantage, it is desirable to effect simultaneously the operations of unrolling one sheet for display and of rolling-up another sheet after display.

The sheet-controlling means employed may have a reciprocatory movement and be effected, for example, by endless belt mechanism, such as chains, the display period being substantially equal to the period occupied by a single traverse of the control means through its circuit.

In the case of endless chain mechanism for operating the sheet control means, it is convenient to dispose a pair of endless chains on opposite sides of the display area and to move the chains unidirectionally at a constant or variable speed, as desired.

Each sheet is rolled upon a spool to which the top horizontal edge of the sheet is anchored and is displayed by being transversely supported adjacent the receiving end of the housing, the lower

edge of the sheet being held captive near the bottom of the housing, so that the sheet hangs substantially vertically from the spool. The displayed or unrolled sheet is carried by its spool on movable supports which are moved at the end of the display period to return the rolled-up sheet to the stack, the rolling-up of the sheet thus supported being preferably effected simultaneously with the unrolling of a second sheet, whilst the lower end of the rolling-up sheet is held captive until released automatically when the second sheet is almost completely unrolled.

The accompanying drawings illustrate, by way of example, one embodiment of the invention, showing a construction utilizing endless chains for sheet control movements.

In the drawings:

Figure 1 is a rear view of the complete apparatus, with the stacked rolls shown at the left and omitted at the right to disclose one sheet in the course of being unrolled for display and another sheet being rolled up after display.

Figure 2 is a vertical cross-section on line II—II of Figure 1.

Figures 3 and 4 are fragmentary side elevations of an apparatus employing endless chains, the two figures showing respectively the position of the mechanism during one instant of the time that one sheet is being rolled up and another unrolled and the position of the mechanism during the display period when the sheet is fully open.

Figure 5 is a fragmentary plan of the mechanism with the component parts in the position shown in Figure 3; and

Figures 6 and 7 show the spool-releasing mechanism and associated means in two more of the positions occupied in the complete cycle.

It will be understood that the mechanism illustrated is duplicated at the opposite sides of the machine, as indicated in Figure 1.

Like reference numerals on the various figures indicate corresponding component parts of the apparatus.

In the construction shown in Figures 1 to 7, the apparatus comprises a vertical rectangular open frame 1. The frame supports a pair of opposed channels 5 wherein are held the axle pins 6 of a number of transversely and horizontally disposed flanged spools 7 which are stacked in the housing constituted by the two channels 5. Each spool 7 carries a flexible sheet 8 of canvas or other suitable material which may carry the printed matter to be displayed or upon which a paper placard or the like may be pasted or otherwise

attached. The sheet 8 is preferably of double or multiple-ply material and between the plies is inserted a spring strip 9 which tends to keep the sheet 8 rolled up. The top edge of the sheet 8 is anchored to the body of the spool 7 while the lower edge is provided with a stiffening rod or bar 10 by means of which this edge is held captive during the sheet controlling operations, as hereinafter more particularly described.

10 The spool 7 carrying the unrolled sheet 8 being displayed is supported by its axle pins 6 in hook-like sockets 20 provided on discs 21 rotatable in one direction only. In order to prevent rotation of the discs in undesired direction there is provided for one of these discs a pawl 20a adapted to engage one of the flat sides 21a of such disc. This pawl is pivoted on a pin 20b carried by the frame 1 and a stop pin 20c extends from said frame to limit the movement of the pawl in one direction. On the inside of the discs 21 are upper sprocket wheels 22 which are located above corresponding lower sprocket wheels 23 for the purpose of traversing endless chain belts 24, motion being imparted to the chains by rotating either 25 of the sprocket pairs 22 or 23 or through other driving means not shown. The sprockets 22 are carried on shafts 22a supported in brackets 22b fixed to the frame 1. The chains 24 each carry spool-supporting brackets 25 and fixed catches 30 or hooks 26 for holding captive the sheet rod 10 during the rolling-up of a sheet 3 after display—see Figure 3. The sheet rod 10 of a sheet during the period it is fully displayed is held captive by pivoted catches 27 mounted near the discharge 35 end of the spool housing. On the chains 24 between the brackets 25 and the catches 26 are mounted rollers 28 which are adapted to contact with abutments 29 on the discs 21 so as to effect a step-by-step or intermittent partial rotation of the discs 21, with the result that the disc socket 20 following that supporting the upper spool 7 which has been on display engages under the axle pins 6 of the spool 7 carried by chain brackets 25. The rotation of the discs 21 also returns the upper spool 7 to the receiving ends of the channels 5. Prior to this intermittent partial rotation of the discs 21, the rod 10 of the rolled sheet 8 is disengaged from the catches 26 as these pass rearwardly over the upper sprockets 22. The 50 mechanism is now in the position shown in Figure 4, which is the position assumed near the end of the fully displayed position, and accordingly shows the empty spool brackets 25 about to operate the means for releasing another spool 7 from the channels 5, and to pick up a spool 7 resting at the lower discharge end of said channels 5. This last-mentioned spool has remained in this position during the simultaneous rolling-up of one sheet after display and the unrolling of the next sheet for display and also during the greater 55 part of the fully unrolled period of the unrolled sheet. Normally the stack of spools is held up by star-wheels 30 with which the spool brackets 25 eventually make contact in passing. Hence, while the spool brackets 25 are moving into position to pick up the waiting spool 7, the next or lowermost spool of the stack is being released singly by the moving star-wheels 30. The released spool moves down into contact with the waiting spool and urges same forward into contact with the pivoted transfer cam 31. This initial depression of the lower end of the cam 31 is followed up and increased by the contact therewith of the roller 28, with the result that by the time the brackets 25 have picked up the

waiting spool, the upper end of the cam 31 has transferred the rod 10 from engagement with the normal detention catches 27 into engagement with the chain catches 26, the catches 27 dropping by gravity into the position shown in Figure 5. A little later the spool in the chain brackets 25 contacts with catches 27 to cause them to engage the rod 10 of the sheet carried by the ascending spool. The chains 24 may have a continuous traverse at uniform speed, or the traverse 10 may be variable as to speed, being accelerated during part of the cycle, for example, during the change-over period from displaying one sheet to displaying another, and slowed or even arrested 15 completely during another part of the cycle, for example, while the displayed sheet is fully exposed.

In practice, the operating mechanism and the stack of spools would be accommodated within a suitable casing having a viewing aperture 20 through which the displayed sheet is visible. A series of these changing signs could be accommodated within a common housing, all the signs being operated by a common power unit, or each or a pair of signs operated by a separate power 25 unit.

It will be appreciated that it is not essential for the spools to be unrolled as they are elevated vertically into the display position, as by inversion of the apparatus and modifications in the 30 mechanism which would be apparent to a skilled workman, the spool could be held while the sheet is unrolled and the spool lowered or raised after an appropriate display period. Alternatively, the spool would be positioned vertically and the sheet 35 unrolled by a sideward movement.

In each of the modified arrangements referred to means for positively traversing the stack of spools through the spool housing would be required.

Sheets displaying "stop-press" news may be shown out of sequence, that is, without waiting for them to traverse right through the housing, by stopping the apparatus at any time and substituting the special sheet for that being displayed or for the waiting spool at the releasing and feeding end of the apparatus.

I claim:

1. In a display device for successively displaying normally rolled sheets, a series of rollers each having end axles, a series of sheets each having one end attached to a roller and its other end provided with a stiffening rod projecting beyond each side of the sheet, a pair of laterally spaced endless chains, supporting and driving wheels for said chains arranged in spaced pairs, means to drive the driving wheels, means on said chains for supporting said end axles, fixed anchorages for engaging the projecting ends of the stiffening rods, other anchorages mounted on said chains adapted to receive the said projecting ends upon disengagement thereof from the fixed anchorages, and rod releasing means for engaging the rod ends and effecting release thereof from the fixed anchorages.

2. The display device of claim 1 wherein the rod releasing means comprises a pair of tilttable members pivoted so as to have their upper ends swing into and out of engagement with the rod ends and having cam surfaces in the paths of 60 said end axles for effecting tilting upon passage of a roller supported by the roller support.

3. The display device of claim 1 wherein there is provided a pair of opposed channels for receiving the axle ends of rollers not in use, a roll 75

transfer device adjacent one end of said pair of channels and including axle end engaging means in the paths of the axle ends carried by the supporting means on the chains, and coacting means on the chains and roll transfer device actuating the latter upon movement of the chains.

4. The display device of claim 1 wherein there is provided a pair of opposed channels for receiving the axle ends of rollers not in use, a roll transfer device adjacent one end of said pair of chan-

nels and including axle end engaging means in the paths of the axle ends carried by the supporting means on the chains, coacting means on the chains and roll transfer device actuating the latter upon movement of the chains, and a single delivery device at the other end of the channels and extending into the path of the axle end supports on the chains, said supports engaging and operating said single delivery device.

GEORGE EDGAR SLACK.
